CLAIM

The ornamental design for a shrouded storage unit, as shown and described.

DESCRIPTION

FIG. 1 is a perspective view of a shrouded storage unit showing our new design;

FIG. 2 is a front elevational view of the shrouded storage unit, the rear elevational view of the shrouded storage unit being identical to the front elevational view shown in FIG. 2;

FIG. 3 is a right side elevational view of the shrouded storage unit, the left side elevational view of the shrouded storage unit being identical to the right side elevational view shown in FIG. 3;

FIG. 4 is a top plan view of the shrouded storage unit; and, FIG. 5 is a bottom plan view of the shrouded storage unit. The broken lines shown in FIGS. 1, 2, and 5 illustrate unclaimed portions of the shrouded storage unit and form no part of the claimed design.

The surface shadings and contour lines shown in FIGS. 1-5 represent the three-dimensional character and contour of the shrouded storage unit. The different surface shadings are used to indicate contrasting appearances.
